UNITED STATES PATENT OFFICE.

HENRY B. HUGHES, OF PHILADELPHIA, PENNSYLVANIA.

GOLD-BEATER'S HAMMER.

SPECIFICATION forming part of Letters Patent No. 402,526, dated April 30, 1889.

Application filed January 31, 1889. Serial No. 298,300. (No model.)

To all whom it may concern:

Be it known that I, HENRY B. HUGHES, a citizen of the United States, and a resident of Philadelphia, Pennsylvania, have invented 5 certain new and useful Improvements in Hammers for Gold-Beating and Metal-Working, of which the following is a full and exact description, reference being had to the annexed drawings, making part hereof.

10 The nature of my invention will fully appear from the following specification and claims.

In the drawings, Figure 1 is a broken plan view of my device, showing the shaft and operative mechanism and one hammer in place.

15 Fig. 1^a is a half cross-sectional view on the line 11 of Fig. 1; Fig. 2, a side elevation (partly in section) showing the hammer part of the actuating mechanism and the cushion with its support; Fig. 3, a detached front view of the cushion attachment.

20 A is the revolving actuating-shaft; B B', fast and loose pulleys, provided with belt C; D, a fixed bearing around the shaft, secured by screws or bolts D' through ears D'' D''' to the beam E, and having a projection, D''', on one side; F, a cam or sinuous groove around the convex surface of projection D'''; G, an oscillating recessed block or sleeve around the end of projection D''', provided with a lug, H, cast 25 integral therewith.

30 I I are pins projecting through sleeve G and engaging in groove F. They are provided with plain necks I' I', which pass through the plain openings in outwardly-screw-threaded nuts or 35 bushings J J, which engage in the female screw-threaded bores in sleeve G. These nuts hold the pins in place.

K is a spline or feather set in the shaft A and engaging loosely in a corresponding 40 groove in part G' of sleeve G, whereby this sleeve is turned by the shaft and with it, while the spline permits its lateral oscillating movement, the latter movement being imparted to it by the action of pin I in sinuous groove F.

45 L is a sleeve loosely enveloping the shaft A, and provided with an annular recess, L'. This sleeve is held in place by rigidly-fixed collars M M' on the shaft; but it turns freely between these collars. A band, N, passes around this 50 sleeve L in groove L', and the ends N' N' of this band hold the "handle" O of the hammer between them.

P is the hammer; Q, the anvil on which the metal to be worked or beaten is set. The hammer is secured to handle O by a band, R, 55 which passes around its neck and is bolted securely to the handle.

S is a cross-bar or block, secured by screws to the surface of sleeve L and adapted to receive the stroke of lug H. 60

T is a set-screw to secure band N to sleeve L and adjust the hammer-handle to a desired angle.

The parts H and S are beveled off at the point H' of their contact to graduate their separation after the stroke. 65

U is a standard supporting cross-beam U', to which latter arm U''' is attached. The latter terminates in a ring. Screw-threaded rod V passes through this ring, and is held in place 70 by screw-threaded nuts V' V', by the turning of which the rod V can be adjusted to various heights.

W W are two long ears from plate W', which sustain the cushion X, which latter in this instance is composed of layers of leather passed several times around pins Y in the ends of ears W W. The butt or back of the hammer strikes this cushion as it is thrown up and rebounds therefrom. This cushion may be made 80 of rubber and other elastic materials or devices, and many forms of cushions will readily suggest themselves to the mind of an ordinarily-skilled mechanic. 75

The pin I, setting in the groove F, is repeated on the other side of sleeve G, and when one of the pins I reaches the extreme F' of the curve or the upper part thereof (as it appears when holding up the drawings) the sleeve G is drawn so far back as to relieve lug H from 90 contact with block S, and as the pin I reaches the lower part of the groove F sleeve G is thrown forward, so that lug H engages with block S to throw the hammer. By elongating sleeve L on the shaft and providing a number 95 of annular grooves, L', therein any desired number of hammers can be rigged thereon, as already described of the one shown, the collar M' abutting, as shown, against the lower end of sleeve L, whatever may be the length of the 100 latter; but as this is mere duplication of what I have shown I shall give it no further description here. By these means my hammers are given a free but certain motion to deliver

their blows and rebound as in the case of hammers manipulated by hand.

The operation is as follows: The belt C, operating pulley B, drives the shaft A continuously in one direction. Spline K upon the shaft similarly revolves sleeve G. Pin travels in groove F, and when at the lower part of the groove (as shown when the drawings are held up) the sleeve G is thrust downward, and lug H strikes block I on the sleeve L, thus suddenly raising the hammer. The lug H is almost immediately relieved or thrown back by the pin I traveling up the curve to the point F' of the groove F. The hammer, which thus receives a throw upward, strikes the cushion X, and is thrown violently back upon the anvil Q, or upon any substance laid upon the latter, from which it rebounds as it does when in the hands of an operator in the ordinary way.

While I speak of the part D''' as an "elongation" of the bearing, it, properly speaking, forms no true part of the bearing as such, but is intended to indicate a stationary sleeve around the revolving shaft, in which may be set the groove F, and I wish the term I use to convey this generic meaning. The cushion X causes the hammer to rebound as the latter strikes it. By loosening set-screw T, thus leaving loose that part of band N which envelops sleeve L, any hammer can be thrown out of operation, as the band N thus becomes independent of the motion of sleeve L. While it would prevent any adjustment of the angle of the hammer-handle by a set-screw, T, the band N might be made polygonal in form, and the part of sleeve L embraced by it may be of corresponding shape; but this would dispense with the set-screw T, while it would obviate reliance on a set-screw to stand the shock of the blow of the hammer without disturbance.

What I claim as new is—

1. The combination of shaft A, elongated bearing D''', provided with sinuous groove F, sleeve G, the said shaft being provided with a feather, K, setting in a corresponding groove 45 in sleeve G to revolve the latter, pin I, engaging a groove, F, lug H, secured to sleeve G, a loose sleeve, L, and hammer-handle O, and hammer P, secured rigidly to sleeve L, and block S, secured to sleeve L, all combined and 50 operated substantially as described.

2. The combination of shaft A, elongated bearing D''', provided with sinuous groove F, sleeve G, the said shaft being provided with a feather, K, setting in a corresponding groove 55 in sleeve G, to revolve the latter, pin I in sleeve G, engaging in groove F, lug H, secured to sleeve G, a loose sleeve, L, and hammer-handle O, and hammer P, secured rigidly to sleeve L, block S, secured to sleeve L, and cushion X, 60 adapted to receive the hammer in its upward throw and to cause its rebound, substantially as described.

3. The combination of shaft A, elongated bearing D''', provided with sinuous groove F, 65 sleeve G, the said shaft being provided with a feather, K, setting in a corresponding groove in sleeve G, to revolve the latter, pin I in sleeve G, engaging in groove F, lug H, secured to sleeve G, a loose sleeve, L, and hammer-handle O, and hammer P, secured rigidly and adjustably by set-screw T to loose sleeve L, and block S, secured to sleeve L, all combined and 70 operating substantially as described.

In testimony whereof I affix my signature in 75 presence of two witnesses.

HENRY B. HUGHES.
